ATTORNEY

UNITED STATES PATENT OFFICE

JOHN BALTIC MOORE, OF ULETA, FLORIDA

AWNING

Application filed May 31, 1929. Serial No. 367,556.

The object of this invention is to provide means for protecting a window and window opening from sun, and from rain and snow, and likewise serving when an all-metal construction is employed as an effective protection against fire.

A further object is to provide a main frame, special means for elevating the frame assumed to have suitable covering of fabric or metal, means for retaining an adjusted position, and pivoted means adapted to depend from the outer edge, and rendering the awning more effective than it would otherwise be as a shield or as a protecting device.

With the foregoing and other objects in view, the invention consists in the novel construction and arrangement of elements disclosed, it being understood that modifications may be made within the scope of the claims without departing from the spirit of the invention.

In the drawings forming part of this application:—

Figure 1 is a view in front elevation, showing an awning of the type under consideration, and showing the operating means, the mounting means, and in dotted lines and full lines a window frame.

Figure 2 is a vertical section on line 2—2 of Figure 1.

Figure 3 is a diagrammatic view on a reduced scale, showing the awning per se in perspective, and showing the arrangement of braces, pulleys, and winding means for the chains adapted to operate vertically slidable elements for controlling the awning.

Figure 4 is a detail in side elevation showing a vertically slidable block, and the connections therefor and the mounting thereof.

Figure 5 is a transverse section thru a channel element adapted to be secured to the window frame and adapted to receive the vertically slidable element.

Figure 6 shows one of the pulleys and a fragmentary portion of a chain carried thereby.

Figure 7 shows one of the pulleys in edge elevation.

Figures 8 and 9 are detail views showing a double sprocket wheel on which the chains at

the lower part of the window opening are positioned and by means of which they are controlled in the required relation for raising and lowering the awning by means of a crank applied to the axial element of the sprocket wheel.

Figure 10 is a detail view showing a retaining tool sprocket wheel.

A portion of a window frame is designated 10, and at the upper portion of the frame I mount a plurality of brackets or the like 11, adapted to receive the end portions of a transverse rod or other element 12 passing thru the side elements 13 of the main frame of the awning.

Carried by the side elements of the main frame is a covering 14 of suitable material, depending upon the particular use to which the awning is to be applied. If protection against sun only is required, ordinary fabric such as that commonly used for the purpose, will be sufficient. If fire protection is desired, light sheet metal, or other fire proof material is to be used.

Connected with the forward portion of the side members 13 are depending devices 15 pivoted at 16 and adapted to receive a strip of fabric or fire proof material 17. This additional element serves an effective purpose in increasing the efficiency of the protecting device, and its position is automatically determined in view of the connections illustrated in Figure 2.

It is desirable that the element 17 should not be of the type which is readily displaced by wind or the like, and I provide therefore a plurality of rods or bars 18 pivotally connected to elements 15, at the point or points 19, the upper ends of the bars 18 being pivoted at 20 to stationary brackets 21 mounted on a window frame.

The bars 22 are pivoted to the main frame of the awning at 23 and at 24 they are pivoted to the slidable devices illustrated in detail in Figures 4 and 5, these elements or slidable devices, designated 25, having the particular construction illustrated, and being adapted to not only slide vertically within the channels 26, but a gripping action results, so that an adjusted position of the awning, deter-

mined by the extent to which the chains are shifted, will be maintained.

15 A plurality of chains will be employed, one on each side of the window frame, and one end of each chain is connected by means of securing device 28 with block 25, and the other end is connected by means of securing device 29 with said block 25.

10 The channels 26 each include a web portion 26' thru which securing device 30 passes. The side walls of the channels are deflected toward each other, or converge near their outer portions, and the extreme edges are outwardly extended at 31.

15 The grooved and flanged portions 32 of the block 25 engage the edge portions of the flanges of the channels, and while there is free vertical movement, due to the lifting action provided by the chain, and a similar 20 movement in a downward direction,—when the elements are at rest, the weight of the awning frame, etc., will serve to cause a binding action, so that adjustment may be maintained.

25 The chains are carried around a plurality of pulleys such as 36, and other pulleys such as 37 positioned adjacent to the lower part of the window frame, and the chains then pass to the double sprocket wheel of Figures 8 and 9, this wheel being designated 38 and having two series of teeth, these series being independently engaged by the chains, and the latter having tension applied thereto in the direction or directions apparent 30 from an inspection of Figure 3. The axial element 39 of the wheel 38 is to be operated by means of a hand crank 40, and the latter is secured by means of the retaining device 41 pivoted at 42 and operating thru the body 40 or socket end 43 of the crank. Engagement of the inner end of the element 41 is within notch 44 in the element 39.

When a window screen is employed, it may be connected with the awning, and both 45 screen and awning elevated at the same time, this arrangement being useful when the windows are to be cleaned, or at other times.

What is claimed is:—

50 1. An awning comprising a main shielding element, rods pivoted to said shielding element, means hinging one end of the element to a building, an auxiliary shielding element hinged to the free end of said main element, 55 links pivoted to the auxiliary element and to the building and adapted to vary the inclination of the auxiliary element relative to the main element by the movement of the latter, 60 slideable supporting means carried by the building and pivoted to the rods to support the shielding elements in their various adjusted positions, and an operating means connected to said slideable supporting means to vary the position of said shielding element.

55 2. An awning including a hinged shield-

ing element, fixed guide members having the sides thereof converging and the free edges disposed laterally to form guide flanges, rods pivoted to the shielding element, brackets pivoted to said rods and provided with flared portions slidably received in the guide members, curved flanges on said brackets and receiving the guide flanges to cooperate with the extensions in slidably connecting the brackets to said guide members and adapted under the weight of the shielding element to effectively grip the guide members to support said shielding element in various adjusted positions, and an operating means connected to said brackets to adjust the shielding element.

In testimony whereof I affix my signature.
JOHN BALTIC MOORE.
